ATTORNEY

UNITED STATES PATENT OFFICE

WILLIAM FINKELSTEIN, OF PHILADELPHIA, PENNSYLVANIA

HAND-BAG FRAME

Application filed June 22, 1925. Serial No. 38,864.

This invention relates to hand bags, and an object of the invention is to provide a novel, practical and suitable construction for connecting the body of the bag to the frame 5 which surrounds the mouth of the bag.

The invention embodies a construction whereby the binding strip is utilized for attaching the entire material of the bag body to the frame, and permits the stitching of 10 the body material to remain in proximity to the upper edge of the frame, to simulate the expensive hand sewed bags, wherein the body extends from the upper edge of the frame and the lining serves to cover the binding 15 strip, eliminating the need and expense of covered binding strips as well as providing a bag structure, which is strong, durable and neat in appearance.

It is to be understood that the particulars 20 herein given are in no way limitative, and that while still keeping within the scope of the invention any desired modification of details and proportions may be made in the construction of the appliance according to 25 circumstances.

The invention comprises further features and combination of parts to be hereinafter set forth, shown in the drawings and claimed.

30 In the drawings:—

Figure 1 is an enlarged fragmentary sectional view through a bag, constructed in accordance with the invention.

Figure 2 is a fragmentary plan view of 35 the bag as in Figure 1.

Figure 3 is an enlarged fragmentary sectional view of a modified form of the invention.

Figure 4 is a detailed sectional view of a 40 further modified form of the bag structure.

Referring to the drawings, the present invention embodies in combination a hinged frame 1 of approved construction, such as is used in forming hand bags or analogous 45 luggage carriers, and which includes right angularly disposed sides 2 and 3, which are covered by leather material 2^a. In the preferred form of invention, a substantial U-shaped strip of leather 4 is placed be- 50 tween the inwardly extending side 3 of the

frame 1 and the binder strip 5, which in the present invention, comprises right angularly disposed sides 6 and 7. A leather filler strip 4^a is fastened between the sides of the U-shaped strip 4. The strip of leather or 55 analogous material 4 is bent to assume an inverted U-shape, and the outer leather covering as indicated at 8 of which the body of the hand bag together with the inner backing 8^a are formed and stitched to the back 60 or bent portion of the strip 4 as shown at 9, and having the outer surface of the body material substantially flush with the outer surface of the frame 1. The cloth lining 10 on the inside of the bag rests against the 65 horizontal sides of the binding strip 5, and it will be seen that the strip 4 will be enclosed within the bag structure and will not be visible, therefore it will be unnecessary to cover the strip. It is also apparent that 70 a bag structure which is relatively strong is provided, and in which the stitching 9 will simulate the more expensive hand sewed type of bag.

In Figure 3 of the drawings, a modified 75 form of the invention is shown in which the outer bag material which together with the lining is bent downwardly between the side 3' of the frame 1' and the side 6' of the binding strip 5' is riveted by means of a rivet 20, to securely connect the body material 8' to the frame 1' and the binding strip 6'. Stitching as identified at 9' may be provided to simulate hand sewed bags and like the preferred form of the invention the body is 80 reinforced adjacent to the frame 1 by the horizontal part 7' of the binding strip 5.

If it is so desired the frame of the bag may be provided with an indented shoulder 30 which receives therein the edge of the body material, as shown in the modified form of the invention, disclosed in Figure 4 of the drawings. In all other respects this latter modified form agrees with the form 85 illustrated in Figure 3 of the drawings.

What I claim is:

In a bag structure, the combination with a mouth surrounding an L-shaped frame, of a bag body comprising an outer leather covering, an intermediate backing layer and 100

inner cloth lining therefor, a strip of sole leather bent upon itself with a spacing strip therebetween to form an inverted U shaped stitching strip adapted to abutt against the inner side of the depending frame portion, a binder strip secured to said depending frame portion with said stitching strip secured therebetween, said bag body having its marginal edge stitched to the creased edge of said stitching strip flush with the outer surface of said frame.

10 In testimony whereof I affix my signature.

WILLIAM FINKELSTEIN.
